CLAIM

The ornamental design for a hand vacuum component, as shown and described.

DESCRIPTION

FIG. 1 is a perspective view of a hand vacuum component showing the new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a bottom perspective view thereof;

FIG. 9 is a right side perspective view of the hand vacuum component shown in FIG. 1;

FIG. 10 is a left side perspective view thereof;

FIG. 11 is a right side rear perspective view thereof;

FIG. 12 is a left side rear perspective view thereof;

FIG. 13 is a top view thereof; and,

FIG. 14 is a bottom view thereof.

The broken lines in the drawings depict portions that form no part of the claimed design.
